THOMAS M. WAYMAN AND GAREY T. WAYMAN, OF PITTSBURGH, PENNSYLVANIA.

SPARKING PLUG.

1,123,631.

Specification of Letters Patent.

Patented Jan. 5, 1915.

Application filed March 1, 1913, Serial No. 751,460. Renewed May 23, 1914. Serial No. 840,644.

To all whom it may concern:

Be it known that we, THOMAS M. WAYMAN and GAREY T. WAYMAN, citizens of the United States of America, residing at Pittsburgh, in the county of Allegheny and State of Pennsylvania, have invented certain new and useful Improvements in Sparking Plugs, of which the following is a specification, reference being had therein to the accompanying drawing.

This invention relates to a sparking plug especially designed for internal combustion engines, commonly styled "gas engines."

Our invention aims to provide:—First, a sparking plug having a movable electrode that is automatically shifted to produce a spark. Second, a sparking plug having a stationary electrode and a pneumatically actuated movable electrode that is held normally retracted relatively to the stationary electrode. Third, a sparking plug having a stationary electrode and a movable electrode which is shifted to an extended position to produce a spark when the cylinder of an engine is charged and shifted to a retracted position when an explosion occurs in the cylinder. Fourth, an automatic sparking device embodying a stationary electrode and a shiftable electrode both of which are compactly arranged in a ported body whereby gases from the cylinder of an engine can be utilized for shifting the movable electrode of a sparking device. Fifth, a pneumatic sparking plug consisting of comparatively few parts that are inexpensive to manufacture, easy to assemble and highly efficient for the purposes for which they are intended.

Our invention further aims to accomplish the above results by a mechanical construction that will be hereinafter specifically described and then claimed, and reference will now be had to the drawing, wherein:—

Figure 1 is a vertical sectional view showing the movable electrode in a retracted position, and Fig. 2 is a similar view showing the electrode in an extended position.

In the drawing, the reference numeral 1 denotes, by the way of an example, a portion of an engine cylinder having the top thereof provided with an opening 2 and arranged within said opening is the inner end of a plug 3.

To retain the plug 3 within the opening 2 said plug is provided with lugs 4 or a lateral

flange that can be secured to the cylinder 1 by screw bolts 5 or other fastening means.

The plug 3 is provided with a longitudinal stationary electrode 6, said electrode being located contiguous to the wall of said plug. The inner end of the electrode has an L-shaped terminal 7 and connected to the outer end thereof by a conventional form of means 8 is a leading-in wire 9.

The plug body 3 is provided with a longitudinal cylindrical bore 10 having the walls thereof, at the inner end screw threaded, as at 11 to accommodate a plug 12, which has a longitudinal opening 13.

The top of the plug body 3 is provided with a cup or housing 14 in communication with the bore 10 through the medium of an opening 15 that aligns with the opening 3 of the plug 12. The cup or housing 14 is normally closed by a detachable cap 16.

Movable in the openings 13 and 15 is a piston rod 17 and this rod, within the bore 10, is provided with a recessed piston head 18. The piston head 18 has packing rings 19 of a conventional form and the recess 20 of said head has the inner end thereof provided with a radially disposed port 21.

The plug body 3 is provided with ports 22 and 23, the former establishing communication between the cylinder 1 and the end of the bore 10, while the latter establishes communication between the cylinder 1 and the bore 10 at a point intermediate the ends thereof.

The end of the piston rod 17, within the cup 14 is provided with a nut or head 24 and encircling said piston rod, between said nut and the bottom of the cup 14 is a coiled compression spring 25, the tension of which is sufficient to hold the piston head 18 in a retracted position, with the port 21 out of registration with the port 23.

Operation:—When gas or an explosive charge is admitted to the cylinder 1 the initial position of the piston head 18 is elevated. As the compression takes place in the cylinder 1 the port 22 admits the mixture above the piston and lowers the piston until the port 21 is in position to register with the port 23. Pressure on both sides of the piston is equalized and the spring 25, which has been compressed during a down stroke of the piston is now free to shift the movable electrode quickly to its initial position, thus breaking circuit which creates a

spark which ignites the charge within the cylinder.

It is thought that the operation and utility of the sparking plug will be apparent without further description, and while in the drawing there is illustrated a preferred embodiment of the invention, it is to be understood that the structural elements are susceptible to such variations and modifications as fall within the scope of the appended claims.

What we claim is:—

1. In a sparking plug, a cylinder, a stationary electrode extending therein, a movable electrode extending into said cylinder, means in connection with said movable electrode whereby the charging of said cylinder shifts said movable electrode toward said stationary electrode to produce a spark, and means in connection with said movable electrode and co-operating with a detonation of the contents of said cylinder in shifting said electrode to a retracted position.

2. The combination with a cylinder, of a plug carried thereby, a stationary electrode carried by said plug and extending into said cylinder, said plug having a chamber formed therein in communication with said cylinder, a spring held movable electrode extending through the chamber of said plug, and a pressure impacted means within said chamber and carried by said movable electrode whereby the charging of said cylinder shifts said movable electrode until the pressure is equalized upon both sides of said means.

3. In a sparking plug, a cylinder, a chambered plug body carried thereby, a stationary electrode carried by said plug body and extending into said cylinder, a piston head movable in the chamber of said plug body and adapted to be shifted within said chamber by a charge in said cylinder until pressure upon both sides of said head is equalized, a movable electrode carried by said piston head, and means at a point removed from said chamber for supporting said piston head in a position to be actuated by a charge from said cylinder.

4. The combination with a cylinder, of a chambered plug body in communication therewith, a stationary electrode extending into said cylinder, a movable electrode arranged longitudinally of the chambered body and adapted to be shifted toward said stationary electrode, and a ported piston head carried by said electrode and adapted to be moved by a charge in said cylinder until the charge in said cylinder enters said ported piston head.

5. The combination with a cylinder, of a chambered plug body in communication therewith, a stationary electrode extending into said cylinder, a movable electrode arranged longitudinally of the chambered body and adapted to be shifted toward said

stationary electrode, a ported piston head carried by said electrode and adapted to be moved by pressure derived by the compressing of a charge in said cylinder until the charge in said cylinder enters said ported piston head, and means placed under tension by a movement of said piston head for restoring said head to its normal position when the pressure derived from the charge is equalized upon both sides of said head.

6. The combination with a cylinder, of a vertical plug body carried thereby, a stationary electrode extending into said cylinder, a spring supported movable electrode carried by said plug body, a piston head carried by said electrode, and movable by impact of pressure derived from the compressing of an explosive charge in said cylinder, said plug body having a port formed therein for the application of pressure from the compressing charge to shift said piston head, and means in connection with said piston head for equalizing the pressure from said charge upon both sides of the piston head whereby said electrode can be elevated.

7. The combination with a cylinder, of a vertical plug body carried thereby, a stationary electrode extending into said cylinder, a spring supported movable electrode carried by said plug body, a piston head carried by said electrode, capable of being shifted in one direction by pressure derived from the compressing of an explosive charge in said cylinder, said plug body having a port formed therein whereby pressure derived from the compressing of the charge in said cylinder contacts with and lowers said piston head, means in connection with said piston head for equalizing upon both sides of the piston head the pressure derived from said charge whereby said electrode can be elevated, and means arranged exteriorly of said plug body for automatically shifting said piston head when the pressure is equalized upon both sides thereof.

8. A sparking plug comprising a fixed electrode, a movable electrode, means whereby said movable electrode is shifted toward said stationary electrode by pressure derived from the compressing of an explosive mixture, means whereby the movement of said movable electrode toward said stationary electrode is arrested at a predetermined point, and means for shifting said movable electrode away from said stationary electrode simultaneously with the arresting of the movement of the movable electrode toward the stationary electrode thereby creating a spark.

9. A sparking plug comprising a stationary electrode, a movable electrode including a piston head adapted to be impacted by pressure derived from the compressing of an explosive charge thereby shifting said movable electrode to engage the stationary

electrode, means whereby the pressure is equalized upon each side of said piston head, and means whereby the movable electrode is automatically shifted from the 5 stationary electrode to create a spark simultaneously with the equalizing of the pressure upon each side of said piston head.

10. A sparking plug comprising a stationary electrode, a movable electrode automatically actuated to engage said stationary electrode by pressure derived from the compressing of an explosive mixture, a tensioning element associating with said movable electrode, and means whereby the pressure 15 acting upon said movable electrode is equalized thereby enabling said tensioning element to shift said movable electrode to form a spark.

11. A sparking plug comprising a stationary electrode, a movable electrode automatically actuated to engage said stationary electrode by pressure derived from the compressing of an explosive mixture, a tensioning element associating with said movable electrode, means whereby the pressure 25 acting upon said movable electrode is equalized thereby enabling said tensioning element to shift said movable electrode to form a spark, and means whereby said tensioning element is adjusted for the producing of a spark at a fixed point during the compressing of the explosive charge.

12. A sparking plug comprising a stationary electrode, a movable electrode, means for supplying pressure against said movable electrode to shift it to the stationary

electrode, means for equalizing the pressure acting upon said movable electrode thereby arresting movement thereof toward the stationary electrode, and means for shifting said 40 movable electrode away from the stationary electrode simultaneously with the equalizing of the pressure thereby creating a spark.

13. A sparking plug including a movable 45 electrode provided with a piston head adapted to have one side thereof impacted by pressure for shifting the electrode toward the stationary electrode, and means whereby the impacting pressure can be equalized 50 upon both sides of the piston head to arrest the movement of the movable plunger.

14. A sparking plug including a movable electrode provided with a piston head adapted to have one side thereof impacted 55 by pressure for shifting the electrode toward the stationary electrode, means whereby the impacting pressure can be equalized upon both sides of the piston head to arrest the movement of the movable plunger, and 60 means for automatically shifting said movable plunger in an opposite direction simultaneously with the equalizing of the pressure upon both sides of the piston head.

In testimony whereof we affix our signatures in the presence of two witnesses.
